CLAIM

The ornamental design for a beverage can with rounded profile and football surface ornamentation, as shown and described.

DESCRIPTION

FIG. 1 is a perspective view of a beverage can with rounded profile and football surface ornamentation showing our new design;

FIG. 2 is a front view thereof;

FIG. 3 is a rear view thereof;

FIG. 4 is a left side view thereof;

FIG. 5 is a right side view thereof;

FIG. 6 is a top view; and,

FIG. 7 is a bottom view thereof.

The end structure depicted by means of broken lines in FIGS. 1, 6 and 7, has been shown for illustrative purposes only and forms no part of the claimed design.

1 Claim, 4 Drawing Sheets
